COIN CONTROLLED CAP REMOVER

Ira H. Fitzpatrick, Austin, Tex., assignor of one-half to James L. Hudgins, Austin, Tex.

Application February 3, 1938, Serial No. 188,559

4 Claims. (Cl. 194—19)

This invention appertains to new and useful improvements in cap removers and more particularly to a cap remover which can only be set for operation by the insertion of a coin.

5 The principal object of the present invention is to provide a coin controlled cap remover for soft drink bottles and the like which will compel the patron to insert a coin equivalent to the price of the drink before he can gain access to the cap remover to permit removal of the cap of the bottle acquired, as for instance, from a self-help ice box.

10 Another important object of the invention is to provide a coin controlled cap remover of the character stated which will be positive acting and substantially fool-proof in operation.

These and various other important objects and advantages of the invention will become apparent to the reader of the following specification.

15 In the drawings:

Figure 1 represents a front elevational view of the apparatus.

20 Figure 2 is a sectional view taken substantially on the line 2—2 of Figure 1 looking in the direction indicated by the arrows.

Figure 3 is an inside elevational view of the shell.

25 Figure 4 is a fragmentary sectional view taken substantially on the line 4—4 of Figure 1 looking in the direction indicated by the arrows.

Figure 5 is a fragmentary detailed sectional view taken substantially on the line 5—5 of Figure 1 looking in the direction indicated by the arrows.

30 Figure 6 is a fragmentary enlarged detailed sectional view taken substantially on the line 6—6 of Figure 1 looking in the direction indicated by the arrows.

Figure 7 is a fragmentary sectional view taken 35 on the line 7—7 of Figure 5 looking in the direction indicated by the arrows.

Figure 8 is a perspective view of the release member.

Figure 9 is a side elevational view of the trigger 40 arm.

Figure 10 is a perspective view of the latch member.

45 Referring to the drawings wherein like numerals designate like parts, it can be seen that 50 numeral 5 denotes the wall to which the apparatus generally referred to by numeral 6 is attached, such as the front wall of a soft drink ice box.

55 The apparatus consists of the plate 7 having suitably secured thereto the strips 8—9 defining together with the plate 10a a coin chute 10, the

lower end of the strip 9 being beveled as at 11 to accommodate the lower end of the vertically rocking trigger arm 12 fulcrumed as at 13 on the plate 7 and which has the spring 14 pulling on the lower end thereof so as to maintain the shoulder 15 at its upper end located under the reduced end portion 16 of the vertically rocking latch arm 17, which arm is fulcrumed as at 18 and provided with the broad latch plate 19 at its outer end alignable with the cap removing lip 20 on the inner side of the hood formation 21, which hood formation 21 is suitably secured as at 22 to the front of the shell 23.

The shell 23 forms a box-like casing for the trigger arm 12, latch arm 17, and other parts 15 presently described and which is open at its back, and upper and lower ends, and suitably secured to said plate 7 in front of the coin chute 10. A slot 23a is provided in the front of said shell 23 from which the latch plate 19 protrudes and which is 20 capped by the hood formation 21 into which said plate 19 extends and which closes the top of said shell.

Numerical 24 represents a vertically disposed release member which is provided with the laterally disposed and beveled finger 25 at its lower end, this release member also being provided with the upstanding leg portion 26 which is pivotally connected as at 27 to a side wall 28 of the shell 23. A tooth 29 at the upper end of the leg 26 normally engages the under side of the latch arm 17 as shown in Figure 6. A spring 30 serves to pull the inner end of the latch member 17 upwardly so as to urge the plate 19 downwardly and normally maintain the reduced end 16 in position to be engaged by the shoulder 15 on the trigger arm 12. 35

The tooth 29 is held in yielding engagement with the arm 17 by the spring 31 suitably connected to the release member 26 and to the wall 28 to urge said member counter-clockwise. 40

As best shown in Figure 7, the lower end of the trigger arm 12 is interposed in the chute 10 at one side thereof in the path of movement of a coin dropping down said chute and to be rocked counter-clockwise by a coin wipingly engaging 45 the lower end thereof, the spring 14 opposing such movement. The latch arm 17 is normally urged clockwise by the spring 30 and movement of said arm 17 counter clockwise is normally blocked by location of the shoulder 15 of the trigger arm 12 50 under the portion 16 thereof. Also the tooth 29 of release member 24 bears upwardly against the under side of latch arm 17 in offset relation to the fulcrum 18 of said arm such that said release member under the urge of the spring 31 opposes 55

clockwise movement of the latch arm 17, the 5 spring 31 and release member 24 balancing said latch arm 17 in substantially horizontal position in opposition to the spring 30, and conversely, the spring 30 and latch arm 17 balancing said member 24. In this balanced condition of the latch arm 17, said arm is yieldingly movable clockwise sufficiently to permit counter-clockwise movement of the trigger arm 12 requisite to removal of the shoulder 15 from under the portion 10 16 and release of said arm 17. During such movement of the latch arm 17 the release member 24 is swung clockwise, the tooth 29 sliding against said arm. In the described balanced condition of the release member 24 the finger 25 thereof is spaced slightly from the plate 7, but in the chute 10, to provide for the requisite degree of clockwise movement of said member 24.

It can now be seen that a coin C dropped down 20 the chute 10 will wipe past the lower end of the trigger arm 12 and cause the latter to swing counter-clockwise sufficiently to release the latch arm 17, after which said coin will lodge on the finger 25. When the latch arm 17 is thus released 25 it may be rocked counter-clockwise against the tension of the spring 30 by engagement of the cap of a bottle thrust upwardly into the hood 21 and against the plate 19. When the latch arm 17 is thus moved, the bottle cap may be engaged with 30 the cap removing lip 20 to remove said cap in the usual manner. As soon as the latch arm 17 is thus rocked the member 24 is released for movement counter-clockwise under the urge of the spring 21 to permit the coin to drop off the finger 25. A depository 33 is provided beneath the shell 33 for receiving the coins. The depository 33 is provided with a window 34 for inspection purposes, and a suitable lock 35 by means of which it may be attached to the lower edge 36 of the shell 33 in any suitable manner.

While the foregoing specification sets forth the invention in specific terms, it is to be understood that numerous changes in the shape, size and materials may be resorted to without departing from the spirit and scope of the invention as claimed 45 hereinafter.

Having described the invention, what is claimed as new is:

1. In a coin controlled bottle cap remover, a 50 casing, a hood-like cap remover on the casing adapted for the insertion of the neck of a bottle thereinto, a closure member for said cap remover pivoted in said casing to extend into the cap remover and for swinging movement in opposite directions into opening and closing positions, respectively, a coin chute extending into said casing,

and means in said casing normally locking said member against opening movement and operative to unlock the same under the control of a coin deposited in said chute.

2. In a coin controlled bottle cap remover, a 5 casing, a hood-like cap remover on the casing adapted for the insertion of the neck of a bottle thereinto, a closure member for said cap remover pivoted in said casing to extend into the cap remover and for swinging movement in opposite directions into opening and closing positions, respectively, a coin chute extending into said casing, and means in said casing normally locking said member against opening movement and operative to unlock the same under the control of a coin deposited in said chute, and including a pivoted trigger arm normally blocking opening movement of said member and movable under the impact of a coin thereagainst from blocking position. 20

3. In a coin controlled bottle cap remover, a casing, a hood-like cap remover on the casing adapted for the insertion of the neck of a bottle thereinto, a closure member for said cap remover pivoted in said casing to extend into the cap remover and for swinging movement in opposite directions into opening and closing positions, respectively, a coin chute extending into said casing, means in the casing normally locking said member against opening movement and operative 30 to unlock the same under the control of a coin deposited in said chute, and means in said casing to block the passage of a coin out of said chute operative under control of said member to release the coin. 35

4. In a coin controlled bottle cap remover, a casing, a gravity coin chute extending into said casing, a hood-like cap remover on the casing for the insertion of the neck of a bottle thereinto, a closure member for said remover pivoted in said casing to extend into said remover and for swinging movement into opening and closing positions, respectively, means in said casing for locking said member against opening movement operative to unlock the same under the impact of a coin 45 gravitating down said chute and including a trigger arm normally engaging said member and imparting under initial operation thereof a limited degree of movement to said member, and means in said casing to block passage of the coin out of said chute comprising a holding dog pivoted for swinging movement into the path of travel of said coin in said chute and operative by said member into said path under movement of the member in said limited degree. 50
